TION OF NEW YORK

OIL RECTIFYING APPARATUS

Application filed November 13, 1928. Serial No. 319,129.

This invention relates to oil rectifying apparatus and has particular reference to apparatus for removing the liquid diluents and deteriorants from the lubricating oil of an internal combustion engine or the like, without removing all the oil from or disturbing the circulation thereof in the engine.

The particular system for rectifying engine lubricating oil to which this invention especially applies is disclosed in our Patent No. 1,717,096, dated June 11, 1929, upon which this application is an improvement. The oil rectifying system as disclosed in the aforesaid patent includes a container through which the oil is circulated by the usual oil pump in forcing the oil from the crank-case of the engine to the bearings and other frictionally engaging parts thereof. This container is provided with a strainer by which solid deteriorants are removed from the oil, and a capillary device such as a wick by which the liquid deteriorants and diluents, such as gasoline and water, are abstracted from the oil by capillary action, leaving the oil to be returned to the engine free of any solid or liquid deteriorants and possessed of its full lubricating qualities. Inasmuch as the gasoline dissolves the oil, the gasoline tends to carry out with it a small percentage of this thinned oil, but a constriction in the wick prohibits this tendency, so that nothing but pure gasoline emerges with the pure water. The water and gasoline thus abstracted are allowed to evaporate into the open air from an enlarged area such as the spread or extended end of the capillary wick or other device employed for the purpose.

While the system described has proven to be eminently satisfactory in every respect for rectifying lubricating oil, further research has developed certain improvements in this system and these improvements form the subject matter of this application. These improvements deal with the facilitation of the capillary action in abstracting the gasoline and water from the lubricating oil of an internal combustion engine, the removal and utilization of the gasoline and water thus abstracted as fuel in the engine, and the automatic introduction of a small amount of the

oil into the engine whereby the operation thereof is improved. It is the principal object of this invention to provide oil rectifying apparatus embodying these improvements.

This object is attained by providing the aforementioned evaporator portion of the capillary device for abstracting gasoline and water from the oil with a suction head fitted with a small air intake and preferably connected to and operated by the intake of the engine or any other source of low pressure. It is preferred that the suction head be connected to the engine manifold, the carburetor, or through an air cleaner to the carburetor. In this way the gasoline recovered from the oil is evaporated by the suction in a small volume of air and may be utilized to advantage as fuel, and the small proportion of the water vapor also recovered in this way slightly moistens the fuel mixture and thus improves combustion. Accordingly, none of the useful by-products of the oil rectifying system are lost and there is no fire hazard due to the free emission and accumulation of gasoline fumes. This is of peculiar advantage in engines where the gasoline leakage into the crank-case is relatively high in that the high gasoline consumption thereof is reduced by a small but constant percentage. Another advantage of the apparatus of this invention is that it increases the capillary activity of the oil diluents in the abstracting device for the reason that the normal air pressure on the device opposing the capillary action is removed. This results in accelerating the abstraction of the diluents and thus improves the effectiveness and efficiency of the entire oil rectifying system.

The invention also contemplates the introduction of oil into the combustion chamber for the purpose of improving the operation thereof. It has been known heretofore that the introduction of lubricating oil into the engine cylinders lubricates the pistons and valves and thus causes the engine to operate more smoothly. Various methods of introducing oil into the engine cylinders have been practiced, and among these is the method of mixing a relatively small proportion of

lubricating oil with the gasoline, and the method of directly introducing special oil into the cylinders by suitable means. These and other methods entail either separate and 5 special apparatus or the additional operation of adding the oil either to the gasoline or to some special apparatus installed for that purpose. By the apparatus of this invention a small but constant supply of the lubricating 10 oil of the engine is abstracted from the lubricating system and introduced into the combustion chamber of the engine. This is accomplished by slightly relieving the constriction in the capillary wick of the oil rectifying 15 device, so that the abstracted gasoline carries with it a small proportion of the oil in solution. In evaporating the abstracted gasoline and water, the suction head connected to the intake of the engine also effects 20 the transfer of the oil with the gasoline and water vapor into the engine where it performs its lubricating function. Thus the modifications of this invention not only facilitate the capillary activity of the lubricating 25 oil diluents and recover the valuable by-products of the device disclosed in our aforementioned co-pending application, but also effect the lubricating of the interior of the engine without the need of separate and 30 special apparatus, a special supply of oil for that purpose, nor attention of any kind. The entire system is devoid of moving parts, fool-proof, and not likely to get out of order.

For a better understanding of the invention, reference is made to the accompanying drawings, in which

Figure 1 is a schematic view showing the application of the oil rectifying apparatus of this invention applied to an internal combustion engine;

Fig. 2 is an enlarged cross-section of the principal elements of the apparatus;

Figs. 3 and 4 are fragmentary schematic views showing different ways of applying the apparatus to an internal combustion engine; and

Fig. 5 is a fragmentary section of a modified form of capillary column.

In these drawings, numeral 10 designates 50 an internal combustion engine from the crank-case 11 of which the lubricating oil is circulated to the various moving parts of the engine 10 by means of the usual oil pump 12. The discharge of the oil pump 12 is divided through pipes 13 and 14, the former 55 acting as a by-pass from pump 12 and leading a portion of the oil to the oil rectifying apparatus, while the latter leads a portion of the oil directly to the bearings and other moving 60 parts of the engine. This arrangement insures lubrication of the engine at all times, and prevents damage by overheating the bearings and the like if the oil rectifying apparatus 15 or any of the oil pipes associated 65 therewith should clog and stop the flow of oil

during operation of the engine. While the oil distributed directly to the engine through pipe 14 has not been immediately purified by the oil rectifying apparatus 15, it has been estimated that all of the engine lubricating 70 oil has previously passed or will pass through the rectifier 15 so that it will eventually all be purified even though divided continuously by the by-pass in the manner described.

The fundamental principles of operation and basic details of construction of the oil rectifying apparatus 15 are described in detail in our aforementioned patent, but will be briefly described here for the purpose of 80 describing the present invention. Referring to Fig. 2, the rectifying apparatus 15 comprises a sheet metal container 16 preferably having the upper edge thereof provided with threads 17 so that it may be removed from 85 sheet metal cover 18 provided with corresponding threads. The disc 19 of top 18 is cup-shaped and formed integrally with a depending tube 20 projecting part way into the container 16, the junction of disc 19 and tube 90 20 forming a raised lip 21. A threaded nut 22, soldered in a depression in top 18, is fitted with intake pipe 13 through which the oil pump 12 discharges oil from engine crank-case 11 into container 16. A hood 23 is soldered to top 18 and forms with disc 19 an air-tight chamber 25 which is sealed around nut 22 by washers 24 held in place by nut 26 which also locks pipe 13 and the adjacent 95 parts in position against loosening and leakage. Threaded through a nut 27 sealed in a depression in the center of hood 23 is a tube 28 connected by nipple 29 to outlet pipe 30 by which the rectified oil is supplied to the engine, as shown in Fig. 1. Pipe 28 extends 100 through tube 20 into container 16 and is in communication therewith.

Between tube 20 and concentric tube 31 is clamped the top edge of filter bag 32 of two 110 ply fabric, the outer ply being of coarse weave while the inner ply is of fine weave and having a fine hair-like nap which engages the outer ply of coarse cloth. As shown in Fig. 2, tube 31 is so shaped as to form an annular 115 space 33 which communicates with the interior of the substantially continuous long tube formed by both tubes 20 and 31. The top edge of filter bag 32 is arranged to communicate with space 33 and the interior of composite tubes 20-31 for reasons to be subsequently explained. Outer tube 31 is constrained upwardly against lip 21 of top 18 to firmly clamp the filter bag 32 by means of a rectangular strap 34 spanning the lower end of tube 31 and held in place by nut 35 threaded on the lower end of discharge pipe 28. A wire yoke 36 embraces the lower end of tube 28 and its free ends keep extended the lower convolution of interior wire coil 37, which, with smaller exterior wire coil 38, forms filter 120 125 130

bag 32 into a bellows shape whereby the bag 32 may expose a large filtering area within the relatively small confines of container 16.

Within the annular space formed between pipe 28 and composite tubes 20-31 is inserted the capillary column 39 which may conveniently take the form of a wick of absorbent cotton cloth or the like, the upper end of which is preferably slit radially and spread to provide a large evaporator surface 40 which lies in cup-shaped disc 19 within chamber 25. A conical nut 41 is adjustably threaded in pipe 28 and cooperates with lip 21 to compress wick 39 to form a neck or constriction therein. The lower end of wick 39 is split around strap 34 and depends therefrom to a point adjacent the bottom of the filter bag 32, being held in position on the legs of yoke 36 by wire rings 42.

Fig. 5 illustrates a fragmentary section of a modified form of the capillary column in which the top edge of the filter bag 32 is sealed from the interior of tube 31 by making tube 20 fit tightly within tube 31. Also, instead of employing one choke nut 41 at the top of wick 39, a second conical choke nut 43 is slidably mounted on pipe 28 and adjustable therealong by nut 44 threaded on the lower end of pipe 28. The cooperation of choke nut 43 with the lower edge of tube 31 compresses wick 39 to form a lower constriction or neck therein.

Referring again to Fig. 2, the top of hood 23 is provided with a second depression in which a nut 45 is airtightly sealed. A T-shaped fitting 46 is tapped into nut 45, this fitting having a bore 47 communicating with chamber 25 and pipe 48. Sealed in fitting 46 and projecting through bore 47 into chamber 25 is a tube 49 provided with an orifice 50 communicating only with the valve chamber 51 and variable in size by screw stud 52 threaded into tube 49. Valve chamber 51 is provided with an air vent 53 normally closed by ball spring valve 54. Pipe 48 is conveniently connected to the intake of the engine 10 whereby a suction is created therein, so that when the engine is operating, ball valve 54 is unseated and air is drawn through vent 53, orifice 50, tube 49, chamber 25, bore 47 and pipe 48. In order to prevent the evaporator portion 40 from being sucked against tube 49, a wire screen 55 is placed over the portion 40.

As disclosed in our aforementioned patent, the capillary column 39 abstracts gasoline and water from the impure oil by capillary action, although the oil also rises as it is diluted by the gasoline which is a solvent thereof, but the percentage of oil dissolved by the gasoline decreases as the mixture rises and what little oil is left is prevented from advancing further by the constricted or necked-in portion or portions of the wick, which allows only the pure gasoline and water to seep through into the evaporator portion 40 of the wick 39. The capillary abstraction and separation of the

gasoline and water from the oil is a natural phenomenon, but the elevation of the liquids in the capillary column is aided by the pressure of the oil caused by pump 12, so that there are two separate forces which procure the effect described, namely, capillary action and the oil pressure. The apparatus of this invention provides a third force which promotes and facilitates the abstraction of the gasoline and water from the oil. This force is a suction applied to the top of the capillary column 40 which aids the oil pump pressure on the base thereof and the natural capillary action. This suction is applied to the column through pipe 48 which communicates with evaporator chamber 25 and air vent 53 in the manner described. The connection of pipe 48 to the intake of engine 10 may be conveniently made to the manifold 56 of the engine 10, as shown in Fig. 1.

The suction thus created in chamber 25 and the accompanying circulation therein of the small amount of air drawn through vent 53 when the engine is operating, serves to rapidly evaporate the gasoline and water abstracted by the capillary column 39 and introduce these vapors into the engine. The air supply may be regulated by adjusting screw stud 52 and is so infinitesimal as to have no appreciable effect on the operation of the engine in the way of diluting or making lean the carburetor mixture. When the engine stops the ball valve 54 is released and its spring instantly closes air vent 53 so that there can be no leakage therethrough, nor can the back-pressure of the engine force any of the combustible mixture into the open air, whereby fire hazards are entirely eliminated. Thus, in addition to promoting and facilitating the capillary activity of the liquids in wick 39, it will be seen that the valuable gasoline vapors which were formerly allowed to escape into the open air are recovered and introduced with the combustible fuel mixture into the engine manifold 56. In addition to the recovery of the gasoline, the fire hazard of allowing the combustible gasoline to evaporate and accumulate under the hood of an automobile engine, for example, is eliminated. The smaller percentage of water vapor also carried by the suction into the engine serves to slightly moisten the combustible mixture and thus improves combustion and the operation of the engine. This phenomenon is familiar to those who have operated an automobile engine at night or in wet weather.

In the modification of the apparatus illustrated in Fig. 2, the filter bag 32, acting as a capillary column, also serves to abstract the liquid diluents from the oil and these diluents traverse the fabric of the bag, ascending to the top thereof, which is restricted or choked between lip 21 of cover 18 and tube 31 so as to allow only the gasoline

and water diluents to pass at this point. The diluents then descend the inserted end of the filter bag and flow into chamber 33 from which they are absorbed by capillary column 39 and eventually pass into absorber portions 40 of the column with the diluents which were directly abstracted by capillary column 39.

Instead of introducing the gasoline and water vapors abstracted from the oil into the manifold 56 they may be introduced into the carburetor 57 by pipe 48, as shown in Fig. 3, thus enriching and moistening the carburetor charge after or during the time that the gasoline introduced by gasoline line 58 is vaporized. Fig. 4 illustrates another way of introducing these recovered gasoline and water vapors into the engine. In this arrangement an air cleaner 59 connected to the air intake of the carburetor is employed, and to this air cleaner the pipe 48 may be connected, whereby the carburetor air is slightly enriched and moistened before entering the carburetor. In short, any suction connection may be applied to hood 23 of the apparatus and for convenience on an internal combustion engine any connection of hood 23 with the intake of the engine may be employed. In this connection, it has been observed that the natural capillary activity of the diluents in the capillary column 39 causes these diluents to be abstracted even when the engine is not operating, although obviously not to the same degree. These diluents, which constitute mostly gasoline, according to accumulate in cup-shaped disc 19, so that when the engine 10 is started, a very rich mixture is introduced immediately into the engine so that the starting of the "cold" engine is facilitated.

As pointed out heretofore and disclosed in our aforementioned patent, the gasoline rising by capillary action in column 39 carries with it in solution a small proportion of the lubricating oil, which, however, is prevented from passing into the evaporator portion 40 of the column by a constriction or constrictions in the columns formed by choke nuts 41 and 43. It has been found that this oil which rises with the gasoline in mechanical solution therewith is a lighter fraction of the lubricating oil of the engine. The engine lubricating oil is cracked during operation of the engine when it comes in contact with the highly heated parts thereof, such as by contact with the under side of the pistons in the splash type of lubrication system, for example. A small percentage of the lubricating oil is thus fractionated into the lighter fractions or derivatives, which return to and mix with the reserve lubricating oil, and a carbonaceous gum, which usually adheres to some point adjacent the seat of the cracking process such as on the undersides or insides of the engine pistons. The gasoline diluent

in the reserve body of lubricating oil has greater molecular affinity for this lighter oil fraction and dissolves the latter more readily than the heavier uncracked lubricating oil, and this lighter oil fraction also has greater capillary activity than the heavy oil, so that it rises most readily with the gasoline in the capillary column. This light oil has a low flash point, and when burned, as in an engine cylinder, it produces very little carbon and unburned gums, so that the advantages obtained by its lubricating qualities are not minimized by the formation of the negligible amount of objectionable residue.

In consideration of these advantages and the phenomena, it has been found that by slightly relieving the constriction or constrictions in capillary column 39 by adjusting nuts 41 or 44, a small but constant proportion of this lighter fraction of the lubricating oil is allowed to pass with the gasoline and water into the evaporator portion 40, and is carried with the other vapors into the engine in the manner described to serve as a lubricant for the pistons and valves. The advantage of lubricating oil in the engine cylinders, especially in a new engine, is well known and has been introduced heretofore by mixing with the liquid gasoline in the storage tank or by separate apparatus provided for that purpose.

In regulating the choke nut 41 in the modification of Fig. 2 in order to allow a small, predetermined quantity of the light fraction of lubricating oil to be introduced continuously into the engine, nut 35 may be adjusted, strap 34 being prevented from turning because of the slot in tube 31 into which it fits, and choke nut 41 being preferably soldered on pipe 28 to prevent oil leakage therethrough and to prevent it from working loose. After it has been adjusted properly nut 35 may be soldered to prevent working loose. In the double choke arrangement for the capillary column shown in Fig. 5, choke nut 41 may be similarly soldered in place while lower choke collar 43 may be adjusted by nut 44, which may also be soldered in place after the constrictions at choke nuts 41 and 43 have been properly regulated.

It will be seen that the apparatus of this invention is simple and most efficient for rectifying lubricating oil rapidly and continuously without disturbing its intended use and circulation, whereby considerable operating economy follows because the oil need no longer be periodically removed and replaced. The apparatus is devoid of moving parts and therefore not likely to get out of order, is inexpensive to make and install, and does not detract from the operation of the engine to which it is attached nor use any expendable power thereof, but, on the contrary, the apparatus improves the economy of the engine by recovering valuable gasoline, and improves

the operation thereof by providing a convenient way of slightly moistening the combustible charge without requiring an additional supply of water or apparatus for that purpose, and by automatically and continuously introducing a small but constant supply of light lubricating oil into the engine cylinders for lubricating the moving parts therein, also without requiring an additional supply of oil or apparatus for that purpose. It is to be understood, however, that the use of the apparatus of this invention is not limited to an internal combustion engine, but may be employed for rectifying oil by capillary action and suction in any conceivable way and arrangement, whether or not it is desirable to recover the gasoline and water vapor mixture. It is also to be understood that the structure and arrangement of the apparatus is not limited to that shown and described, but the invention is susceptible of many changes, such as arranging the filtering and evaporator units in the manner disclosed in the aforesaid co-pending application, and the like.

We claim:

1. In oil rectifying apparatus, the combination of a container for the oil, a capillary device in the oil in said container, for abstracting liquid diluents from the oil, and a source of suction connected to the device for removing the abstracted diluents therefrom.

2. In oil rectifying apparatus, the combination of a container for the oil, a capillary device in the oil in said container for abstracting liquid diluents from the oil, an evaporator connected to said device for evaporating the diluents abstracted thereby, and suction means connected to the evaporator for removing the vaporized diluents therefrom.

3. In oil rectifying apparatus, the combination of a container for the oil, a capillary device in the oil in said container for abstracting liquid diluents from the oil, an evaporator connected to said device for evaporating the diluents abstracted thereby, and a source of suction connected to the evaporator for removing the vaporized diluents.

4. In oil rectifying apparatus, the combination of a container for the oil, a capillary device having a part extending into the oil in said container for abstracting and elevating liquid diluents from the oil by capillary action, means for introducing the oil into the container, and suction means for removing the abstracted diluents from the top of said devices.

5. In oil rectifying apparatus, the combination of a container for the oil, a capillary device having a part extending into the oil in said container for abstracting and elevating liquid diluents from the oil by capillary action, means for introducing the oil into the

container, an evaporator for the abstracted diluents at the top of said devices, and suction means connected to the evaporator.

6. In oil rectifying apparatus, the combination of a container for the oil, a capillary device for abstracting and elevating liquid diluents from the oil, pressure means for introducing the oil to the container, and suction means connected to the top of the device.

7. In oil rectifying apparatus, the combination of a capillary column for abstracting and elevating liquid diluents from the oil by capillary action, means for introducing the oil to the base thereof, a source of positive pressure acting on the oil at the base of the column, and a source of negative pressure acting on the top of the column.

8. In oil rectifying apparatus, the combination of a porous column for abstracting and elevating liquid diluents from a body of oil by capillary action, means for supplying oil under pressure to the column, and means for removing the abstracted diluents from the column under vacuum.

9. In oil rectifying apparatus, the combination of a porous column for abstracting and elevating liquid diluents from a body of oil by capillary action, a source of positive pressure connected to the base of the column, and a source of negative pressure connected to the top of the column, whereby the capillary activity of the liquids in the column is promoted.

10. In an oil rectifying system, the combination of an oil pressure line, an oil filter therein for removing the solid diluents from the oil, a porous body projecting into the line for removing the liquid diluents therefrom by capillary action, and a source of suction connected to the body for promoting capillary action therein.

11. In apparatus for rectifying the lubricating oil of an internal combustion engine, the combination of a porous body having a portion projecting into the oil for removing the liquid diluents therefrom by capillary action, and means connecting another portion of the body to the intake of the engine, whereby the suction thus applied to the body promotes the capillary activity of the diluents therein.

12. In apparatus for rectifying the lubricating oil of an internal combustion engine, the combination of an oil pump, a container connected thereto, a porous body in the container and projecting down into the body of the oil for abstracting the liquid diluents from the oil therein by capillary action, said body having a portion projecting from the container, and connections between said portions of the body and the intake of the engine, said connections including an air intake.

13. In apparatus for rectifying the lubricating oil of an internal combustion engine, the combination of an oil pump, a pipe con-

- ected to the pump for supplying oil to the engine, a by-pass for said pipe, a porous body having a portion extending into said by-pass for abstracting the liquid diluents from the oil by capillary action, said body having a portion extending out of the by-pass, and connections between said last-named portion and the intake of the engine.
14. In apparatus for rectifying the lubricating oil of an internal combustion engine, the combination of an oil pump, at least two lines for supplying oil from the pump to the engine, means in one of said lines for abstracting the liquid diluents and a small quantity of the oil, and means connected to said first means for introducing the abstracted diluents and oil into the engine.
15. In internal combustion engine having a reserve body of lubricating oil, the combination of a wick having one end immersed in the oil for abstracting the liquid diluents therefrom by capillary action, and connections between the other end of the wick and the intake of the engine for vaporizing and introducing the vaporized diluents to the engine.
16. In an internal combustion engine having a reserve body of lubricating oil, the combination of a capillary column having one end immersed in the oil for abstracting the liquid diluents and a small quantity of oil therefrom, and means connected to the other end of the column for conveying said diluents and small quantity of oil into the engine.
17. In an internal combustion engine having a crank case, a body of lubricating oil in said crank case, the combination of means for abstracting a quantity of the oil from said reserve body and means connected to said first-mentioned means for introducing this quantity of oil into the engine.
18. In an internal combustion engine having a reserve body of lubricating oil, the combination of means for separating the liquid diluents from the oil, means for regulating said first-named means to allow a small quantity of oil to be abstracted from the body of the oil, and means for conveying these abstracted diluents and oil to the engine.
19. In an internal combustion engine having a reserve body of lubricating oil, the combination of a capillary column immersed in said body for abstracting the liquid diluents therefrom, an evaporator head for the column, an air vent therein, and connections between the head and the intake of the engine for evaporating the diluents with air in said head and conveying the vaporized diluents into the engine.
20. The method of recovering diluents from the lubricating oil of an internal combustion engine, which consists in abstracting the diluents from the oil by capillary action, vaporizing the diluents, and introducing them into the engine.
21. In oil rectifying apparatus, the combination of a container for the oil, a bag of porous material therein for filtering the oil and abstracting the liquid diluents therefrom by capillary action, and means connected to the bag and extending outside of said container for conducting the abstracted diluents from said bag outside of said container.
